UNITED STATES PATENT OFFICE.

MARTIN BALCKER, OF CHICAGO, ILLINOIS, ASSIGNOR TO MARQUETTE TOOL & MFG. CO., A CORPORATION OF ILLINOIS.

MULTIPLE-DRILL-PRESS-CONTROLLING MEANS.

1,401,388.

Specification of Letters Patent. Patented Dec. 27, 1921.

Application filed December 18, 1919. Serial No. 345,823.

To all whom it may concern:

Be it known that I, MARTIN BALCKER, a citizen of the United States, residing at Chicago, in the county of Cook and State 5 of Illinois, have invented certain new and useful Improvements in Multiple-Drill-Press-Controlling Means, of which the following is a specification.

This invention relates to improvements in 10 multiple drill press controlling means of the pneumatic type, and one of the objects of the invention is to provide an improved device of this character which may be readily applied to a multiple drill press, 15 and by means of which the drill head may be raised and lowered and the mechanical feeding mechanism of the press may be automatically thrown into operation at the proper points in the travel of the drill head. 20 A further object is to provide an improved device of this character by means of which the drill head will be arrested in its movement toward the work to permit the adjustment or positioning of the drills 25 with respect to the jig.

To the attainment of these ends and the accomplishment of other new and useful objects as will appear, the invention consists in the features of novelty in substantially the 30 construction, combination and arrangement of the several parts hereinafter more fully described and claimed and shown in the accompanying drawings illustrating this invention, and in which:

35 Figure 1 is a side elevation of an apparatus of this character showing the same applied to a drill press, portions of the drill press being diagrammatically represented in elevation.

40 Fig. 2 is an enlarged detail view of the cylinder and valve controlling means as taken from the left hand side of Fig. 1.

Fig. 3 is a top plan view of the parts shown in Fig. 2.

45 Fig. 4 is an enlarged detail elevation of the tripping mechanism showing the parts in two different positions.

Fig. 5 is a detail elevation as taken on line 5—5, Fig. 6.

50 Fig. 6 is a top plan view of the parts shown in Fig. 5.

Fig. 7 is a detail sectional view of the cylinder and piston.

Referring more particularly to the drawings the numeral 10 designates generally a

portion of a drill press frame having a drill head 11 mounted for reciprocation thereon and a controlling element 12 by means of which the mechanical feeding mechanism of the drill head is controlled. 60 The drill head 11 is counterbalanced in the ordinary and usual manner, and all of the parts above referred to are of the ordinary and well known type.

The controlling mechanism consists primarily of a cylinder 13 of any desired size and configuration but is preferably provided with a bottom 14 having a port 15 leading from the cylinder to the outside thereof, and a head 16 also provided with a 65 port 17 communicating with the interior of the cylinder at the end thereof. The head 16 is provided with a recessed portion 18 having an opening 19 therethrough and in which recess and opening is arranged a 70 gasket or packing 20, the latter surrounding the piston rod 21 and is adapted to be clamped against the piston rod by means of a suitable nut or bushing 22 provided with external screw threads adapted to engage the threads 23 on the wall of the recess in the head 18. Reciprocating within the cylinder 13 and connected to the piston rod 21 is a piston 24 of any suitable construction, but is preferably provided with a body 75 portion 25 of a diameter considerably smaller than the diameter of the cylinder and projecting from the periphery of the portion 25 intermediate the ends of the body 24 is a circumferential flange 26 which is 80 of a diameter slightly smaller than the internal diameter of the cylinder so that the periphery of the flange or portion 26 will stand adjacent the cylinder wall. Substantially U-shaped annular flexible packing 85 members 27 are arranged on opposite sides of the flange 26 to encompass the body portion 25 of the piston. The open sides of these elements 27 are arranged adjacent the respective ends of the body portion of the 100 piston and one wall of each of the annular members 27 stands adjacent the cylinder wall. These elements 27 may be held against displacement in any suitable manner but preferably by means of flanges or 105 shoulders 28 on the ends of the piston body 25 which overhang the adjacent wall of the respective elements 27. With this construction it will be manifest that as the piston is reciprocated in one direction or the other, 110

the action of the fluid within the cylinder will force the wall of the element 27 against the cylinder wall.

Fluid is supplied to the cylinder 13 from any suitable source through a pipe 29 having branches 30-31 leading respectively to the ports 17-15. Arranged within the branch 30 is a three-way valve 32 of the ordinary and well known construction, and which valve is adapted when in predetermined positions to form communication between the pipe 29 and the top of the cylinder and when in another position is adapted to cut off the connection between the pipe 29 and the top of the cylinder and establish communication between the top of the cylinder through the valve 32 and outlet opening 33 discharging into the open air.

A similar valve 34 is arranged in the connection 31 between the pipe 29 and the port 15 at the other end of the cylinder. This valve 34 is of the three-way type and when in one position establishes communication between the pipe 29, through the connection 31 to the end of the cylinder and when the valve is in another position will cut off this latter communication and will establish communication between the end of the cylinder through the port 15 and to the open air through an opening 35 in the valve case.

Links 36-37 are respectively connected with the valves 32-34 and another link 38 is pivotally connected by its respective ends to the links 36-37 so that when the link 38 is actuated in one direction or the other the links 36-37 will be correspondingly actuated and the valves will be shifted thereby.

An operating arm 39 is provided for actuating the valves. This arm 39 is pivotally supported intermediate its ends as at 40 upon a suitable support 41. One end of the arm 39 terminates adjacent the link 38 and is provided with a slot 42 adapted to receive a pin or fastening device 43 so as to form a loose connection between the arm 39 and the link 38. Connected with the other end of the arm 39 by means of a pivot 44 is a bar or rod 45.

The parts thus specifically described are supported in any desired or suitable manner preferably above the frame 10 of the press and such supporting means may embody a supporting platform 46 held in position by means of suitable uprights 47, which latter are in turn supported by means of suitable brackets 48 secured to the drill press frame.

The rod 45 passes through suitable guides 49 and terminates at any desired point adjacent the base 50 of the frame. Connected at the lower end of the element 45 is a link 51 the free end of which is pivotally connected as at 52 to a rocking support 53, which latter is pivotally supported intermediate its ends as at 54 upon a suitable fixed support. A dog 55 is pivotally supported intermediate

its end preferably by the pivot 54, the end 56 of the dog projecting above the element 53 and is provided with a shoulder 57 which is adapted to be brought into engagement with the element 53 to rock the latter when the dog 55 is rocked about its support in one direction and in a manner to be hereinafter described and for the purposes to be set forth.

This dog 55 is adapted to be rocked or shifted preferably by means of a foot treadle 58 pivotally supported as at 59 in any convenient position for the operator. The treadle is connected by means of an arm 60 through the medium of a link 61 with the lever 62 pivotally supported intermediate its ends as at 63, one end of the lever being connected as at 64 with the link 61 and the other end of the lever 62 is connected by means of a link 65 to the dog 55, one end of the link 65 being pivotally connected as at 66 with the lever 62 and at 67 with the dog 55, a spring 68 being anchored at one end as at 69 with the element 53 and by its other end as at 70 with the dog 55 for normally holding the shoulder 57 of the dog out of engagement with the element 53. Thus it will be seen that with the construction thus far described the valves 32-34 may be controlled by the operation of the treadle 58 in the following manner. When the operator depresses the treadle 58 in the direction indicated by the arrow in Fig. 1, it will be seen that the lever 62 will be rocked in a direction to move the shoulder 57 of the dog 55 against the element 53 against the stress of the elastic element 68. A continued movement of the parts in this same direction will cause the element 53 to be rocked about its pivot 54 to draw down upon the rod 45 to shift the lever 39 and through the medium of the link 38 and links 36-37, will rock the valves 32-34 to establish communication between the inlet pipe 29 and the top of the cylinder 13 to admit fluid into the top of the cylinder on one side of the piston 24, which will cause the piston to descend. At the same time the valve 34 will be so adjusted as to cut off communication between the pipe 29 and the other end of the cylinder and will establish communication between the lower end of the cylinder 13 and the outlet 35 to permit the fluid on the lower end of the piston to be discharged into the atmosphere as the piston descends so as not to retard the descent of the piston.

As the piston thus descends it will lower the drill head 11 and in order that this movement of the piston may be communicated to the drill head there is provided a yoke 71 which is connected with the piston rod 21 above the end 16 of the cylinder. Connected to one end of this yoke 71 is a bar or rod 72 which extends below the

cylinder and along one side of one of the uprights of the press frame 10. This bar or rod 72 is connected with the drill head 11 so as to move the drill head and also so that it is adapted for an independent movement with respect to the drill head. To that end there is provided on the drill head 11 spaced guides 73—74 through which the bar or rod 72 loosely passes. These guides 10 73—74 are spaced for a considerable distance from each other and secured to the rod intermediate the guides and for movement with the rod is a collar 75 which may be adjustably positioned upon the rod in any 15 suitable manner such as by means of fastening devices or screws 76. An elastic element such as a coiled spring 77 encompasses the rod 72 with one end resting against the guide 74 and the other end resting 20 against the end of the collar 75. The tension of this elastic element 77 is such that it will normally hold the collar 75 against the guide 73 and when the rod 72 is lowered by the piston in the manner just 25 above described, the tension of the elastic member is such that under normal conditions it will not yield but will force the head 11 downwardly toward the work. When, however, the movement of the drill 30 head is arrested by reason of the drills coming into contact with the work, and when the piston and rod 72 continue their downward movement, the elastic member 77 will yield and permit the rod 72 to continue in its 35 downward movement independently of the drill head 11.

Carried by the rod 72 preferably adjacent the guide 73 is an adjustable collar 78 which is adapted, when the rod 72 moves independently with respect to the drill head 11, to engage the end of a rod 79. Connected with this rod 79 are spaced arms 80—81 which stand astride of the controlling element or lever 12 of the mechanical feeding mechanism of the press and which mechanical mechanism is of the ordinary and well known type usual in machines of this character. The rod 79 may be guided by suitable guides, preferably the guides 73—74 and if desired an additional guide 82 may be connected with the rod 79 to stand astride of and move against the adjacent portion of the rod 72. With this construction and as the rod 72 continues in its downward movement independently of the head 11, it will be seen that the collar 78 will engage the end of the rod 79 and will shift the latter. This shifting movement, downwardly, of the rod 79 will cause the arm 80 to shift the controlling element 12 and set the mechanical feeding mechanism into operation for operating the drill.

Connected also with the yoke 71 and operating preferably on the other side of the frame 10 is a bar or rod 83 which

operates through suitable guides and is of a length to terminate adjacent the rocking support 53 and carried by this bar 83 is a collar 84 having a shoulder 85. The collar is adjustably supported by the rod 70 83 by means of a suitable fastening device 86 whereby the position of the collar may be varied with respect to the rod 83. Arranged within the path of movement of the shoulder 85 of the collar 84 is a pawl 87 75 which is pivotally supported as at 88 upon the rocking support 53 and a spring 89 may be provided between the dog 55 and the pawl 87 which tends normally to maintain the end of the pawl 87 within the path of 80 movement of the shoulder 85. Secured also to the bar or rod 83 at any desired distance above the collar 85 is another collar 90 which may be adjustably secured to the bar or rod by means of a suitable fasten- 85 ing device 91. In order to trip the pawl 87 when the dog 55 is rocked about its pivot 54 any suitable connection may be provided between the two such for instance as an element 92, one end of which is connected with the pawl 87 and the other end passes through a suitable guide 93 carried by the end 56 of the dog 55 and the extremity 94 of the element 92 is preferably deflected as shown to prevent the parts from 95 separating. Thus when the dog 55 is rocked about its pivot under the influence of the operation of the treadle 58 it will be seen that the end 56 of the dog will pull upon the element 92 and shift the pawl 87 100 against the stress of the spring 89. At the same time the pawl 87 is adapted to move independently with respect to the dog 55 when the collars 90—84 are passing the dog on the upward movement of the rod 83, 105 and this independent movement will be accomplished by reason of the fact that the element 92 will slide loosely through the guide 93.

It is thought that the operation of this improved structure will be clearly understood from the foregoing, but briefly stated it is as follows:

Work to be operated on is placed beneath the drill head 11, and assuming the drill 115 head to be in its elevated or uppermost position, with the piston 24 adjacent the top of the cylinder 13, and the jig or pattern by which the work is to be drilled is in position upon the work and below the drills, the 120 operator first actuates the treadle 58 in the direction indicated by the arrow in Fig. 1. This operation will, through the bar 61, lever 62, and link 65, shift the dog 55 to the left in Fig. 1 and to the right in Fig. 4. The 125 shoulders 57 will engage the rocking support 53 to rock the same about its pivot 54 and this rocking movement of the element 53 will, through the medium of the link 51, draw down the bar or rod 45 which will 130

rock the lever 39 and shift the valves 32-34 so as to establish communication between the inlet pipe 29 through the valve 32, into the top of the cylinder 13. At the same time 5 the links 38-37 will shift the valve 34 to open the bottom of the cylinder on the other side of the piston to the atmosphere. With the parts in this position the fluid will enter the pipe 29 into the top of the cylinder 10 to move the piston 24 downwardly. As the piston moves downwardly, the drill head 11 will also be given a downward movement toward the work. This downward movement of the head and piston will continue 15 until the shoulder 85 of the collar 84 strikes the end of the pawl 87 which projects into the path of the downward movement of the shoulder, as shown more clearly in Fig. 4. The piston and head will continue a short 20 distance farther toward the work or sufficiently far to depress the pawl 87 to rock the rocking support 53 about its pivot 54. This will cause the rod 45 to be shifted upwardly and this upward movement of the 25 rod 45 will rock the arm 39 in the opposite direction and the arm will in turn through the medium of the slot 42 and pin 43 connection with the link 38, shift the latter to rock the valve 32 so as to cut off communication 30 between the pipe 29 and the top of the cylinder 13 and establish communication between the top of the cylinder and the opening 33 which discharges into the atmosphere. This will arrest the movement of the piston 35 and the drill head 11. This arresting movement can take place at any predetermined point in the travel of the head and piston according to the position that the collar 84 is located upon the rod 72. It is preferable 40 to arrest the movement of the drill head a short distance in advance of the engagement of the drill with the work. This is done so as to permit the operator to adjust the drills with respect to the jig.

45 After the drills have been thus adjusted, the operator then actuates the treadle 58 in the same direction or in the direction indicated by the arrow in Fig. 1 to rock the dog 55 and cause its shoulder 57 to engage the 50 rocking support 53 to draw down upon the rod 45 and reestablish communication between the inlet pipe 29 of the cylinder to the top of the cylinder to force the piston farther downwardly. This rocking movement of the dog 55 takes place when the 55 end of the pawl 87 is under the shoulder 85 of the collar 84 and it will be seen that as the end 56 of the dog 55 is swung about the pivot 54 the dog will through the medium 60 of the element 92 actuate the pawl 87 about its pivot 88 against the stress of the spring 89 to move the end of the pawl away from the collar 85 so as to permit the piston, the drill head, and the rod 72 to be further 65 lowered so that the drills will engage the work. The drill head will then continue in its downward movement until the drills engage the work and as the drills do engage the work, the movement of the head 11 will be arrested before the piston in the cylinder 70 travels to the limit of its downward movement. The rod 72 will then be shifted relatively with respect to the drill head through the medium of the collar 75 and elastic element 77, in the manner set forth. Just as 75 the head 11 is arrested by engagement of the drills with the work, and as the rod 72 continues to move with respect to the head the collar 78 on the rod 72 will engage the bar 79 to shift the latter downwardly until the 80 arm 80 engages the controlling element or lever 12 to shift the latter at which time the mechanical feeding mechanism of the drill press, will be thrown into operation to effect the drilling.

85 The actuation of the mechanical feeding mechanism is controlled by shifting the lever 12. On the downward movement of the head, the pressure upon the bar 79, in the manner just described causes the arm 80, to rock the lever 12, about its pivot 12^a, and this lever, through the medium of the link 12^b, will rock the yoke 12^c, about its pivot 12^d, in a direction to cause the yoke to engage and shift the shaft 12^e, about the pivot 90 12^f. Keyed upon the shaft 12^e, to rotate therewith, but so as to be shifted longitudinally of the shaft, is a worm 11^a, that is adapted to be moved into mesh with a worm wheel 11^b, carried by the head 11.

95 Connected to rotate with the worm wheel 11^b, is a gear 11^c, that engages with a rack 11^d, carried by the upright 10.

100 Thus when the parts are shifted as above indicated and the worm 11^a, engages the worm wheel 11^b, the head will be fed downwardly by the mechanical feed when motion is imparted to the gear through the shaft 12^e. The arm 81 serves merely as a support to support the weight of the element 12 when 110 the latter is shifted.

115 It is during the drilling operation that the collar 90 on the rod 83 will engage the end of the pawl 87 and just at about the completion of the drilling this collar 90 will shift the pawl 87 to rock the rocking support 53 to move the rod 45 in the opposite direction from its direction of operation by the treadle 58, or in the same direction that it will be shifted by the collar 84. 120 This will cut off communication between the inlet pipe 29 and the top of the cylinder and connect the top of the cylinder with the outlet opening 33 to the atmosphere. At the same time that the valve 32 is being 125 shifted to exhaust the top of the cylinder, and the collar 90 is moving the pawl 87, the valve 34 will be shifted so as to establish communication between the inlet pipe 29 and the bottom of the cylinder 13 to 130

permit the fluid to enter the cylinder under the piston. During this admission of the fluid under the piston, the drill head is still continuing its downward movement under the influence of the mechanical feed, to the end of the drilling operation, due to the fact that the mechanical feeding mechanism overcomes the air pressure under the piston at that time. This continues until the me-

chanical drilling controlling element 12 is shifted to render the mechanical feeding inactive. To that end there is provided a suitable stop device 95 mounted upon a suitable support 96 preferably carried by the frame of the machine and which stop device is arranged in the path of the downward movement of the controlling element to shift the latter while the drill head 11 continues in its movement.

20 As the lever 12, is thus shifted, it will through the medium of the link 12^b, rock the yoke 12^c, in the opposite direction about its pivot to cause the yoke to move away from the shaft 12^a, so that the shaft will be caused to rock about the pivot 12^c, to move the worm 11^a, out of mesh with the worm wheel 11^b, the pitch or angular surface of the teeth of the worm wheel tending to shift the worm and shaft.

25 30 If desired and in order to carry the weight of the shifting rod 45 and the parts co-operating therewith, a suitable suspension device 97 such as an expansion spring may be provided, one end of which may be anchored to a suitable fixed support and the other end may be anchored to a collar 98 carried by the rod 45.

While the preferred form of the invention has been herein shown and described, it is 40 to be understood that various changes may be made in the details of construction and in the combination and arrangement of the several parts, within the scope of the claims, without departing from the spirit of this 45 invention.

What is claimed as new is:—

1. In combination with a drill press embodying a traveling drill head, mechanical means for operating the same and means 50 for controlling the said operating means; of fluid actuated means for shifting the said head independently of the first said means, means for controlling the operation of the fluid actuated means, and means operating automatically at two different predetermined points in the same direction of travel of the said head under the influence of the said fluid actuated means for controlling the latter.

60 2. In combination with a drill press embodying a traveling drill head, mechanical means for operating the same and means for controlling the said operating means; of fluid actuated means for shifting the 65 said head independently of the said me-

chanical means, means for controlling the operation of the fluid actuated means, and means operating automatically at predetermined points in the same direction of travel of the said head under the influence 70 of the said fluid actuated means for controlling the latter, the said fluid actuating means being also operable to move the drill head in opposite directions.

3. In combination with a drill press embodying a traveling drill head, mechanical operating means therefor, and means for controlling the said operating means; of fluid actuated means for shifting said head independently of the said operating means, 80 means for controlling the operation of the fluid actuated means, and means operating automatically to also control the said fluid actuated means, the said automatically operating means embodying spaced elements 85 adapted to become successively active at different predetermined points in the same direction of travel of the said head.

4. In combination with a drill press embodying a traveling drill head, mechanical operating means therefor, and means for controlling the said operating means; of fluid actuated means for shifting said head independently of the first recited means, mechanism for rendering the said fluid actuated means active to move the head in one direction, and means operatively related to the said mechanism and responsive in its operation to the operation of the said head to render the said fluid actuated means inactive at two different predetermined points 100 in the same direction of travel of the said head.

5. In combination with a drill press embodying a traveling drill head, mechanical operating means therefor, and means for controlling the said operating means; of fluid actuated means for shifting the head independently of the first recited means, mechanism for rendering the said fluid actuated means active to move the head in one direction, means operatively related to the said mechanism and responsive in its operation to the operation of the said head to render the said fluid actuated means inactive, 115 at a predetermined point in the travel of the said head, and means operatively related to the said mechanism, and rendered active by a further movement of the head in the same direction of travel whereby the direction of operation of the said fluid actuated means may be reversed.

6. In combination with a drill press embodying a traveling drill head and means for controlling the feeding movement there- 125 of; of fluid actuated means for also feeding said head, mechanism operable at will to render the said fluid actuated means active, means operating at a predetermined point in the travel of said head under the influence 130

of the said fluid actuated means for rendering the latter inactive to arrest the feeding movement of the head thereby, and means operating at another predetermined point in the same direction of travel of said head under the influence of the said fluid actuated means to render the latter inactive to arrest the feeding movement of the head thereby and to cause the operation of the fluid actuated means to be reversed to retract the head from the work.

7. In combination with a drill press embodying a traveling drill head and means for controlling the feeding movement thereof, of fluid actuated means for also feeding said head, mechanism operable at will to render the said fluid actuated means active, means operating at a predetermined point in the travel of said head under the influence of the said fluid actuated means for rendering the latter inactive to arrest the feeding movement of the head thereby, and means operating at another predetermined point in the same direction of travel of said head under the influence of the said fluid actuated means to render the latter inactive to arrest the feeding movement of the head thereby and to cause the operation of the fluid actuated means to be reversed to retract the head from the work, the said mechanism and the third and fourth recited means embodying a trip device and spaced elements operating in unison with the said head for successively actuating the said trip device.

8. Mechanism for controlling a drill press head embodying fluid actuated means for moving the head, means for rendering the fluid actuated means active to advance the head to the work, a controlling element separate from the fluid actuated means, means whereby the said fluid actuated means will operate independently of the said head to shift the said controlling element when the movement of the head under the influence of the fluid actuated means is arrested by the work to be operated upon by the drills, and means whereby the said mechanism will again be set in motion until the completion of the drilling operation.

9. Mechanism for controlling a drill press head embodying fluid actuated means for moving the head, means for rendering the fluid actuated means active to advance the head to the work, a controlling element separate from the fluid actuated means, means whereby the said fluid actuated means will operate independently of the said head to shift the said controlling element when the movement of the head under the influence of the fluid actuated means is arrested by the work to be operated upon by the drills, the third recited means embodying a yielding connection between the said head and the said fluid actuated means, and means whereby said mechanism will again be set in

motion until the completion of the drilling operation.

10. Mechanism for controlling a drill press head embodying fluid actuated means for moving the head, means for rendering the fluid actuated means active to advance the head to the work, a controlling element separate from the said fluid actuated means, means operating automatically to render the fluid actuating means inactive at a predetermined point in the movement of the head, means whereby the said fluid actuated means will operate independently of the said head to shift the said controlling element when the movement of the said head under the influence of the said fluid actuated means is arrested by the work to be operated upon, and means whereby the mechanism will be again set in motion until the completion of the drilling operation.

11. Mechanism for controlling a drill press head embodying fluid actuated means for moving the head, means for rendering the fluid actuated means active to advance the head to the work, a controlling element separate from the said fluid actuated means, a connection between the said head and the said fluid actuated means, said connection embodying an element for moving the head and adapted for a relative movement with respect thereto, a shoulder on the element, an elastic element disposed between said shoulder and a fixed part of the head whereby the first said element will advance the head, said elastic element being adapted to yield to permit the first recited element to move independently of the head when the latter is arrested by the work to be operated upon, and means whereby the said relative movement of the first recited element with respect to the said head will shift the said controlling element.

12. Mechanism for controlling a drill press head embodying fluid actuated means for moving the head, means for rendering the fluid actuated means active to advance the head to the work, a controlling element separate from the said fluid actuated means, a connection between the said head and the said fluid actuated means, said connection embodying an element for moving the head and adapted for a relative movement with respect thereto, a shoulder on the element, an elastic element disposed between said shoulder and a fixed part of the head whereby the first said element will advance the head, said elastic element being adapted to yield to permit the first recited element to move independently of the head when the latter is arrested by the work to be operated upon, means whereby the said relative movement of the first recited element with respect to the said head will shift the said controlling element, and means embodying the second recited means for causing the said fluid

actuated means to actuate the said head in the opposite direction.

13. In combination with a drill press embodying a traveling drill head, mechanical means for operating the same and means for controlling the said operating means; of fluid actuated means, means connecting the said fluid actuated means with the head for moving the latter and for also permitting a relative movement of the head and fluid actuated means one with relation to the other, means for controlling the operation of the fluid actuated means, and means operating automatically at two different predetermined points in the same direction of travel of the said head under the influence of the said fluid actuated means for controlling the latter.

14. In combination with a drill press embodying a traveling drill head, mechanical operating means therefor, and means for controlling the said operating means; of fluid actuated means for shifting said head

independently of the first recited means, mechanism for rendering the said fluid actuated means active to move the head in one direction, means operatively connected to the said mechanism and responsive in its operation to the operation of the said head to render the said fluid actuated means inactive at two different predetermined points in the same direction of travel of said head, the last recited means embodying a dog, an element pivoted intermediate its ends, said dog being pivoted to the said element at one side of its pivot, a controlling bar connected with the said element on the other side of the pivot and adapted to be shifted when the said element is rocked by the dog, and means operable upon the said element for also shifting said bar.

In testimony whereof I have signed my name to this specification on this 13th day of December, A. D. 1919.

MARTIN BALCKER.
